UNITED STATES PATENT OFFICE

ANTHONY A. RIECK, OF MILWAUKEE, WISCONSIN, ASSIGNEE OF ONE-THIRD TO IRWIN
W. COX, OF DENVER, COLORADO

MEMORIAL MARKER

Application filed June 26, 1931. Serial No. 547,038.

The present invention relates to memorial markers, gravestones and the like.

Among the objects of the invention is to provide a novel memorial marker, or grave-stone or the like, which may lie on or overlie a grave, preferably to the whole extent or full size of the grave, and which will be artistic in appearance, and have as permanent parts thereof such elements as ornamental inlays, a legend member, an emblem, and/or means for holding a floral piece, as desired. A bounding frame, preferably of metal may also be engaged at the edges of the marker. The marker may rest on the ground of the grave, or be supported on members located in the ground of the grave so that any sagging of the grave will not affect the position of the marker.

Other objects, advantages, capabilities and features are comprehended by the invention as will later appear and as are inherently possessed thereby.

Referring to the drawings:

Fig. 1 is a top plan view of a marker constructed in accordance with the invention;

Fig. 2 is a longitudinal sectional view of the same, taken in a plane represented by line 2-2 in Fig. 1 of the drawings;

Fig. 3 is a transverse sectional view of the same, taken in a plane represented by line 3-3 of Fig. 1 of the drawings;

Fig. 4 is a transverse sectional view of an alternate form of marker having a convex or water-shedding top;

Fig. 5 is a fragmentary transverse sectional view showing an alternate form of frame bounding the marker; and

Fig. 6 is a view of a plug which may be used in winter in lieu of the vase.

Referring more in detail to the drawings, the embodiments selected to illustrate the invention are shown in the form of a plate, slab or tablet comprising a layer 1 of concreted material, such as concrete or other similar moldable and solidifiable substance, and a layer of ornamental inlay elements 2. The latter may be of any shape, size, color, material, and thickness, as desired. In the illustrative embodiment they are shown as colored square pieces of tile. They are laid

on the slab 1 and bonded thereto, and to each other by any suitable bonding material, such as cement 3. If desired the joints among the elements 2, may be leaded so that the colored elements and the leaded joints 65 may give a church-window effect. In this way the elements 2 form an inlay or mosaic for the marker or tablet. Any design may be effected by suitable arrangement of different colored and shaped elements 2. 60

For the purpose of protecting the edges of the marker, and also to enhance the esthetic appearance of it, a frame 4 preferably of non-corrodible metal, is provided about the edges of the marker. Suitable reinforcing 65 and anchoring elements 5 and 6 are secured to the frame 4 and embedded in the material 1. This frame may be a plain band about the edges of the tablet, or may have an inwardly directed flange 7 embedded in the 70 material 1, such as is shown in Fig. 5. Also, the frame 1 whether or not it has a flange 7, may also have at the upper surface of the marker, an outwardly directed flange 8, such as is shown in Fig. 5. This flange 8 will 75 act to ward off close growing grass and also act as a guide when cutting the grass. In this way the grass will not overhang the border portions of the marker.

While the top of the marker may be flat, 80 it may also be raised, curved, slanted, or convexed so as to shed and drain off water or the like, such as is clearly shown in Fig. 4.

The marker may lie flat upon the ground of the grave, but should the ground sink 85 or sag, the marker may also be displaced. To avoid this, it is preferable to separately support the marker, as upon posts 9, such as pipes, driven into the ground 10, the upper ends 11 of the posts 9 being a given distance 90 below the top 12 of the ground. These posts are preferably located a given distance from the sides of the marker. See Fig. 3. At the ends of the marker are provided supporting members which may be in the form of cross 95 bars 13 having anchors 14 embedded in the material 1, the cross bars 13 being in engagement with the underside of the marker, and having depending leg portions 15, and outwardly extending feet 16, with depending toes 100

17 extending into the tops 11 of the posts 9, the feet 16 resting or being supported upon the tops 11 of the posts 9. If desired, cross pins 18 may be inserted through suitable apertures in the posts 9 and toes 17 to lock the parts together, as is clearly shown in Fig. 3.

The marker preferably has means for a legend. This may be in the form of a plate 19 of any suitable material, such as metal, and having a border portion 20, an intaglio 21, and cameo data or legend elements such as words or names 22 and dates 23. This legend member 19 may also have anchor elements 24 embedded in the material 1. It will be noted that this plate 19 forms an inlay element among the inlay elements 2, with the top surfaces even with each other.

Also, if desired an inlay emblem or the like may be likewise set among the element 2. The emblem selected for illustration in this invention is shown in the form of a Christian cross 25 preferably of metal. It lies on the surface of the material 1 and may have anchor elements 26 embedded in the material 1. This emblem also forms an inlay element among the inlay elements 2, their top surfaces being preferably even.

A means for holding flowers, a floral piece or the like may also be provided. Such a means may comprise a metal member 27 having lugs or fins 28 embedded in the material 1. It is preferable that this member 27 extend through the layers 1 and 2 of the marker and be provided with a threaded aperture 29 for the engagement of the threaded lower end portion 30 of a vase 31, the latter being preferably of metal. The vase 31 is preferably open at its lower end for the draining of water, and also to permit the passage of a growing plant rooted in the ground portion 32 beneath the opening 29, in case a plant is desired to be used instead of placing a bouquet of flowers in the vase 31. In winter, the vase may be removed, and a plug 33 may be inserted in place to close the opening 29. This plug may have a decorative top, as having an initial 34, or an emblem, or the like.

The emblem 25 may be of any desired form or kind, such as a fraternal, patriotic, religious, or similar emblem.

While I have herein described and upon the

drawings shown illustrative embodiments of the invention, it is to be understood that the invention is not limited thereto but may comprehend other structures, details, arrangements of parts, forms, and features without departing from the spirit thereof.

Having thus disclosed the invention I claim:

1. A memorial marker for graves, comprising a slab extending horizontally over the grave, inlay elements inlaid in the top surface of said slab and including ornamental elements and legend elements, bonding means for said elements and so united to said slab as to hold said elements thereto, and supporting means for said slab, said supporting means including elements constructed and arranged to be embedded in the ground and located at positions adjacent said slab and outwardly spaced with respect to the edges thereof.

2. A memorial marker for graves, comprising a slab extending horizontally over the grave, inlay elements inlaid in the top surface of said slab and including ornamental elements and legend elements, bonding means for said elements and so united to said slab as to hold said elements thereto, a metal frame bounding the edges of said slab, reinforcing means embedded in said slab and secured to said frame, and supporting members having portions thereof embedded in said slab for securing thereto and having supporting portions disposed in the ground at the sides of the grave and adapted to rest upon supports located in the ground for supporting said marker over the grave.

3. A memorial marker for graves, comprising a slab extending horizontally over the grave, inlay elements inlaid in the top surface of said slab and including ornamental elements and legend elements, bonding means for said elements and so united to said slab as to hold said elements thereto, a metal frame bounding the edges of said slab, reinforcing means embedded in said slab and secured to said frame, supporting posts in the ground at the sides of the grave, cross pieces secured to the bottom of said slab and having the end portions thereof extending beyond the sides of the slab and the grave and resting upon said posts for supporting the marker over the grave.

ANTHONY A. RIECK.
